UNITED STATES PATENT OFFICE

JOHN WILLIAM HARTER, OF PELHAM BAY PARK, NEW YORK, ASSIGNOR TO MACARTHUR CONCRETE PIPE CORPORATION, OF NEW YORK, N. Y., A CORPORATION OF NEW YORK

APPARATUS FOR SETTING PILES

Application filed May 22, 1929. Serial No. 365,012.

This invention relates to apparatus for setting piles.

Piles are often constructed from pipe by driving the pipe in the ground or bed to receive the pile and thereafter filling the pipe with concrete. In ordinary practice, piles are driven by means of pile hammers which are operated either by raising by means of rope or cable and being permitted to fall on the pile of its own weight, or by automatic hammers operated by steam or compressed air. These hammer blows cause considerable vibration in many soils and often endanger adjoining or adjacent structures, the vibration causing cracks or settlement of the same.

This invention has for its salient object to facilitate the driving of piles and to accomplish the operation with a minimum of vibration.

Another object of the invention is to provide apparatus of the type specified, so constructed and arranged that the device is adapted for use in driving pipe of different sizes.

Further objects of the invention will appear from the following specification taken in connection with the drawings, which form a part of this application, and in which

Fig. 1 is an elevational view of one form of apparatus constructed in accordance with the invention;

Fig. 2 is an elevational view taken at right angles to Fig. 1;

Fig. 3 is a perspective, diagrammatic view illustrating the operation of the pulling cable by means of which the piles are pulled into the ground;

Fig. 4 is a plan view of the block adapted to rest on the top of the pipe to be driven; and

Fig. 5 is an elevational view, partly in section, showing the upper end of a pipe and the block resting thereon.

The invention briefly described consists of a method of and apparatus for driving piles, so constructed and arranged that a steady or continuous downward pull is exerted on the pile in addition to the driving action of a pile hammer. The two forces for driving the pile may operate simultaneously or either

may be used alone. The apparatus is further so constructed that the block or member which rests on the upper end of a pipe to be driven is adapted to be used in conjunction with different sizes of pipes.

Further details of the invention will appear from the following description.

In the particular form of apparatus illustrated in the drawings, the mechanism for pulling down and driving the piles is carried by a frame consisting of a base 10 and an upright frame 11, suitably braced, as by struts 12.

The base 10 is preferably mounted on rollers 15, which in turn are supported by suitable frame work, such as I-beams 16. The I-beams are mounted on supports 17 of any suitable construction. A cross frame member 18 connects the upper ends of the upright frame members 11 and a sheave 20 is rotatably mounted in a bracket 21 mounted on the frame member 17.

A block 25 is slidably mounted between the upright frame members 11 and has recesses 26 at the two edges thereof to receive the members 11. The block 25 has formed thereon and depending therefrom, a plurality of ledges A, B and C of different sizes, adapted to coact with different diameters of pipes. The block has a pair of horizontal openings 30 and 31 extending therethrough and in these openings are mounted sheaves 32 and 33.

In order to exert a continuous downward pull on the pipe to be driven, a flexible cable 35 has its ends 40 and 41 secured to a suitable fixed abutment, such as the support 17, and passes around the sheaves 32 and 33, downwardly around a pair of sheaves 42 and 43 which are connected to one of the supports 17 and upwardly around a sheave 45. The sheave 45 is carried by a yoke 46 connected to a cable 47 which extends upwardly and around a sheave 48 carried by the cross frame member 18. From the sheave 48 the cable 47 passes to a suitable winch or drum, by means of which force can be exerted thereon.

In order to provide for the use of a pile hammer in conjunction with the continuous downward pull exerted by the cable mecha-

nism above described, a hammer 50 of any suitable construction is suspended from a cable 61 which passes upwardly and around a sheave 20. The cable 61 can be slackened off as the pipe is driven so as to bring the hammer into cooperative relation with respect to the block 25 on which it operates.

It will be evident from the foregoing description that by the use of the apparatus described, or other suitable apparatus, a pipe or pile may be driven by exerting a continuous downward force thereon or by the continuous downward pull in conjunction with the intermittent driving action of a pile hammer. In this manner the driving of the pile can be accomplished in a minimum amount of time and the amount of vibration caused by the operation can be materially reduced. Furthermore, it will be noted that the block which transmits the forces to the pile is adapted for use with pipes of different diameters.

Although one specific embodiment and one particular form of apparatus for carrying out the method have been particularly shown and described, it will be evident that the invention is capable of modification and that other apparatus may be utilized for carrying out the method without departing from the spirit or scope of the invention, as expressed in the following claims.

What I claim is:

1. Apparatus of the character described comprising a block adapted to fit on the upper end of a pipe, flexible means for exerting a downward pull on said block, and a hammer disposed above and in operative relation to said block during the operation of said pulling means, said pulling means operating on the block independently of said hammer.

2. Pile driving apparatus comprising a frame, a block slidably mounted therein, means for exerting a continuous downward force on said block, and a pile hammer mounted for coaction with said block simultaneously with said means, said force exerting means operating on the block independently of said hammer.

JOHN W. HARTER.
